UNITED STATES PATENT OFFICE.

WILLIAM GATEWOOD ADAMS, OF ROANOKE, VIRGINIA.

BRIDGE CONSTRUCTION.

1,252,873.

Specification of Letters Patent.

Patented Jan. 8, 1918.

Application filed October 26, 1916. Serial No. 127,867.

To all whom it may concern:

Be it known that I, WILLIAM GATEWOOD ADAMS, a citizen of the United States, and resident of Roanoke, Virginia, have invented certain new and useful Improvements 5 in Bridge Construction, of which the following is a specification.

My invention is designed for the reinforcing of old bridges to divide up the 10 strain and weight or load by arranging new girders or trusses in juxtaposition with those to be reinforced and having one set of girders or trusses carry one part of the load and the other set of girders or trusses 15 carry the other part of the load, this being accomplished by supporting the ties or transverse beams or groups of ties or transverse beams—that would otherwise rest entirely upon the old girders or trusses, some 20 entirely on one pair of girders or trusses, and some on other pair, that is, as having one tie, or group of ties, supported by one pair of deck girders and having no supported connection with the other pair, 25 while the next tie, or group of ties, will be supported from the second pair of girders and having no supported connection to the first pair, and so on.

In the accompanying drawing

30 Figure 1 is a perspective view of a bridge reinforced according to my method, and in

Fig. 2 I have shown a simple diagram to further illustrate the invention.

In strengthening or reinforcing of 35 bridges, where it may be desirable to place a new girder by the side of an old girder so as to have the new one carry part of the load, such provision is not considered efficient, for the reason that when it would 40 otherwise be advisable to reinforce the girder, it is not possible to so adjust the bearings of the several loads on the two girders, as to enable the designer to definitely determine what part of the load is 45 being carried by one or the other of the girders, and the custom is, therefore, to usually remove the old girder and replace it by a new one, simply to increase its capacity to meet the demands of an increased 50 loading.

It is my purpose to distribute the load in such a way as to be able to render mathematically determinate the resulting strains produced in each girder for the loads imposed, and in carrying out my invention in 55 the reinforcement of an old railroad bridge,

as shown in Fig. 1, the girders G' represent the old structure, while the girders G^2 are my improved reinforcement, which, in the present instance, I have shown as inter- 60 posed between the outer girders suitably braced to each other.

The railway tie A supporting its portion of loads on rails along lines C will be supported upon the inserted girders by means 65 of blocks between the under face of the tie and the upper face of the girders, and these blocks will support the tie in a position above the level of the outer girders. The next tie will be blocked upon the outer 70 girders and will have no supporting connection with the inner girders, and so on, and thus one-half of the load will be sustained by the outer girders and the other half by the inner girders, or any proportion 75 of the load, as, of course, two or more ties may be supported in succession from the outer set of girders and a corresponding number in succession from the inner girders, or a greater number of ties may be sup- 80 ported from one than from the other set, or the left hand outer with the right hand inner girder may act together to support parts of the load while the other two sup- 85 port the remainder.

In Fig. 2 I have shown the invention dia- 90 grammatically in connection with a bridge structure, in which deck trusses are utilized to support the transverse beams, and in like manner one beam or group of beams will be supported by the outer trusses and the next beam or group of beams by the inner trusses through suitable blocks, and thus the weight of the load adjusted to meet the requirements of the structure, varying, as 95 found best adapted to capacity of trusses, the number and location of beams, that are supported by either pair of trusses.

Though the figures indicate only deck 100 structures, it is my intention to apply this reinforcement to through bridges. In which cases, for through girder or truss design, the new and through reinforcing girders, or trusses, will be placed preferably out- 105 side of the old and the intermediate or cross beams, carrying the loads to girders, or trusses, will be suspended below the girders or trusses, or will pass through the trusses, provision being made, always, as in cases of deck girders and trusses, for having each 110 cross beam supported only by two of the trusses, whether it be by one old truss and

one new truss or by two old trusses or by two new trusses, the words "truss" or "trusses" meaning also "girder" or "girders."

5. What I claim is:—

The hereinbefore described method of reinforcing trusses or girders consisting in dividing the reactions of transverse load transmitting beams, or ties, that have been, 10 or would otherwise be borne by the original truss or girder, into separate and distinct

groups, and introducing to help bear these reactions, new trusses or girders placed in juxtaposition to the old ones and having the transverse load transmitting beams, or ties, so connected to the individual trusses, or girders, that each group of reactions will be entirely borne by one truss or girder independent of support by any other truss or girder, substantially as described.

In testimony whereof I affix my signature.

WILLIAM GATEWOOD ADAMS.
